PHONOGRAPH RECORD CHANGER BASE

Earl E. Hoyt, Northvale, N.J., assignor to BSR (U.S.A.)
Limited, Blauvelt, N.Y., a corporation of New York

Filed Dec. 2, 1968, Ser. No. 14,732

Term of patent 14 years

Int. Cl. D14—01

U.S. Cl. D56—4

Fig. 1.

← 4

Fig. 2.

Fig. 3.

Fig. 4.

Fig. 5.

FIG. 1 is a perspective view of a phonograph record changer base embodying the new design, showing also record changer structure in dashed lines.

FIG. 2 is a plan view of the record changer base of FIG. 1.

FIG. 3 is a vertical section on line 3—3 of FIG. 2.

FIG. 4 is a vertical section on line 4—4 of FIG. 2.

FIG. 5 is a fragmentary vertical section on lines 5—5 of FIG. 2.

The broken line showing of a representative record changer mechanism in FIG. 1 is for illustrative purposes only.

I claim:

The ornamental design for phonograph record changer base, as shown and described.
